UNITED STATES PATENT OFFICE.

WILLIS S. SHERMAN, OF MILWAUKEE, WISCONSIN, AND WILBER E. RICHARDSON, OF NEW YORK, N. Y., ASSIGNORS TO SIGHT FEED OIL PUMP COMPANY, OF MILWAUKEE, WISCONSIN, A CORPORATION OF WISCONSIN.

OIL-PUMP MOTOR.

No. 821,196.

Specification of Letters Patent.

Patented May 22, 1906.

Application filed February 23, 1904. Serial No. 194,680.

To all whom it may concern:

Be it known that we, WILLIS S. SHERMAN, residing in Milwaukee, in the county of Milwaukee and State of Wisconsin, and WILBER E. RICHARDSON, residing in New York, in the county of New York and State of New York, have invented a new and useful Improvement in Oil-Pump Motors, of which the following is a description, reference being had 5 to the accompanying drawings, which are a part of this specification.

This invention relates particularly to certain new and useful improvements in oil-pump motors, but broadly covers improvements in motors for any purpose, and has for its object to provide operating means having movable support from a moving body and capable of imparting motion to an operated means by reason of the difference in the effect 15 produced by the movements of the body on the support and on the operating means, such difference in effect being due to the inertia of the operating means.

Another object of this invention is to provide a moving body carrying an actuating means mounted to be movable with relation to the moving body and means connecting the body and the said actuating means adapted to receive motion as the result of the 25 inertia of the actuating means during the movements of the body.

Another object of this invention is to provide a machine oil-feed pump or the like with an automatic operating means adapted 35 to impart motion to such oil-feed pump or similar device during the movements of the machine only and receiving its impulse from such movements of the machine.

A further object of this invention is to accomplish the above results by means of a 40 movable weight the inertia of which renders it less susceptible to the influence of the movements of the engine than its support and the difference in the effects produced by such 45 movements on the weight and on its support being utilized to operate the pump.

Another object of this invention is to vary the degree of effect produced by the motor, as by rendering the actuating means for the 50 weight-operated lever-arm adjustable toward

or away from the operating-shaft controlled by said lever-arm.

With the above primary and other incidental objects in view the invention consists of the devices and parts and their equivalents as hereinafter set forth.

In the accompanying drawings the figures represent side elevations of two modifications of oil-pump motors embodying the principles of this invention and applied to a 60 sight-feed oil-pump such as is shown and described in Letters Patent to Wilber E. Richardson, No. 661,323, dated November 6, 1900.

Figure 1 shows a form of the invention in which the lifting force of a suspended weight 65 is opposed by a second weight, and Fig. 2 shows a form of the invention in which the lifting force of a suspended weight is opposed by a spring.

In the drawings, 1 represents the oil-pump, 70 which may be of any desirable type and which is bolted or otherwise rigidly secured to a supporting means 2, such as the cab of a locomotive or any other body, preferably receiving motion from the mechanism supplied with oil by the pump, and 3 is the shaft of said oil-pump, which is capable of operating the pump mechanism when given slight oscillations. A sleeve 4 is fixed upon the shaft 3 and held rigid therewith by 75 means of a nut 5, threaded on said shaft and preferably binding the sleeve upon a shouldered squared portion of the shaft. A socket 6 is provided on said sleeve, in which a lever-arm 7 is secured in any suitable manner.

An angular bracket 8 is given rigid support either, as here shown, upon the pump 1 or in any other manner or place, and in a perforation of its projecting upper end, which overhangs the lever-arm 7, is loosely mounted an 80 eyebolt 9 with its eye portion lowermost and its nut 10 resting upon the upper surface of the bracket. A link 11 has its upper looped end coupled to the eye of the eyebolt 9 by a ring 12, and its lower looped end engaged in 85 the upper projecting eye 13 of a weight 14, preferably a solid metal ball. The lower eye 13 of said weight connects with the upper looped end of a link 15, and the lower looped end of said link 15 engages with a perforation 90

in the ear 16 of a collar 17, which is slidably mounted on the lever-arm 7, said collar being held in its adjusted positions by a set-screw 18, threaded therethrough and engaging the lever-arm 7. The upper link may be suspended from any desired portion of the movable body and may have any desired length as compared with the lower link. For instance, the upper link may be suspended 10 from the ceiling of the cab and may be much shorter than the lower link, so that a greater lift for a given motion of the ball-weight 14 may be imparted to the lever-arm 7 than would be accomplished by a longer link, owing 15 to the shorter radius of swing of the ball-weight. The fact that the sway of the cab is greater at such point results in an increased degree of movement of the ball-weight 14, and so may be preferred. A weight 19, also 20 preferably formed of a solid metal ball, has a central bore therethrough with a sliding fit on the lever-arm 7, and its collar 20, rigid therewith or secured thereto, carries a set-screw 21 to engage the lever-arm 7, so that the ball-weight 19 may be adjusted on the lever-arm nearer to or farther from the shaft 3. The bracket 8 is provided with a lateral extension 22, by which the said bracket is mounted upon the pump 1, said extension 30 having longitudinal slots 23 therein, through which extend bolts 24, capable of rigidly clamping the extension 22 to the casing of the pump 1 when the proper adjustment is accomplished.

35 The form of invention shown in Fig. 2 is similar to that shown in Fig. 1, except that the weight 19 is omitted and in place thereof a coiled spring 25 is employed, its upper hooked end engaging the perforation of the 40 depending ear 16' of the collar 17', corresponding to the collar 17 of Fig. 1, and the lower hooked end of said spring engaging the eye of an eyebolt 9', mounted in the under bracket 8', similar to the corresponding parts 45 above. The bracket 8' has the lateral extension 22' adjustably bolted to the under side of the pump-casing 1 or in any suitable manner or place in the same manner as with the extension 22.

50 In operation while the supporting means 2 is making quick horizontal motions, such as are common with a locomotive-cab when under way, the inertia of the ball-weight 14 tends to prevent its participating in such 55 movements, and as the pump takes the movement of the support the result is that said weight draws upwardly upon the collar 17, thereby oscillating the shaft 3 by means of the lever-arm 7. The weight 14 being suspended 60 from the bracket 8 by means of the link connection 11 is free to swing as a pendulum, and in such movements its link connection 15 with the lever-arm 7 causes said lever-arm to oscillate the shaft 3, and so operate the oil-pumping mechanism, the weight

19 serving to restore the lever-arm 7 to its normal position after having been swung upwardly by the weight 14, as just described. It will be seen that the degree of movement of the lever-arm 7 depends upon the degree 70 of movement of the weight 14, and should it be found that in a particular case the extent of movement of the parts in their relative adjustments is not sufficient to give the oil-pumping mechanism its desired operation 75 the bracket 8 may be adjusted nearer to the shaft 3 by loosening the bolts 24 and sliding the bracket extension 22 to the left, as shown in the drawings, and at the same time loosening set-screw 21 and sliding the collar 20 8c along the lever-arm 7 toward the shaft 3 to a corresponding extent. In their new adjustments the parts are again secured, and for the given amount of swing of the weight 14 relative to the other parts the lever-arm 7 is 85 swung to a greater extent than before, inasmuch as the collar 17 receives the same amount of vertical pull from the weight 14 and operates in a shorter radius. As the result the degree of oscillation of the shaft 3 is 90 increased, and by it the operation of the pumping mechanism is correspondingly increased.

With the construction shown in Fig. 2 the operation is the same as that of the construction just described, the spring 25 serving to oppose the pull of the weight 14 and to return the lever-arm 7 to its horizontal position after being lifted by said weight 14. The adjustments of this form of device are also similar to those described for the form shown in Fig. 1, with the exception that it is also necessary to adjust the bracket 8' in the same manner that bracket 8 is adjusted, so as to keep the two brackets in alinement.

While the part 2 has been referred to herein as the "movable support or body," it is obvious that the bracket 8 and pump 1, which are intended to have a rigid connection therewith, and therefore partake of the movements, may be considered as movable bodies or movable supports; and it is with the understanding that these terms "movable support" and "movable body" are sufficiently broad to cover any body or support capable of movement or designated to receive movement that they are employed in the following claims. Such terms are not intended to render the combinations incomplete without the presence of a moving engine or cab or other body by which the parts may be carried.

What we claim as our invention is—

1. A movable support, a weight suspended therefrom, an operated means connected 125 with said weight and with the support, and a weight opposing the tendency of the first-named weight to move the operated means as the result of the inertia of said first-named weight during the movements of the support. 130

2. A movable support, an operating-shaft suitably journaled thereon, a lever-arm carried by the operating-shaft, and a weight having a yielding connection with the movable support and with the lever-arm.
3. A movable support, an operating-shaft suitably journaled thereon, a lever-arm carried by the operating-shaft, and a weight movably suspended between the lever-arm and the movable support and connected therewith.
4. A movable support, an operating-shaft suitably journaled thereon, a lever-arm carried by the operating-shaft, a bracket mounted on the movable support, and a weight suspended between the bracket and the lever-arm and connected therewith.
5. A movable support, an operating-shaft suitably journaled thereon, a lever-arm carried by the operating-shaft, a bracket adjustably mounted on the movable support, and a weight suspended between the bracket and the lever-arm and connected therewith.
6. A movable support, an operating-shaft suitably journaled thereon, a lever-arm carried by the operating-shaft, a bracket adjustably mounted on the movable support, a weight suspended from the bracket and having adjustable flexible connection with the lever-arm.
7. A movable support, an operating-shaft suitably journaled thereon, a lever-arm carried by the operating-shaft, a bracket mounted on the movable support, and a weight having link connections with the bracket and with the lever-arm.
8. A movable support, an operating-shaft suitably journaled thereon, a lever-arm carried by the operating-shaft, a bracket mounted on the movable support, an eyebolt adjustable through a perforation of the bracket, a link having pivotal connection with the eyebolt, a weight having pivotal connection with the link, a collar on the lever-arm, and a link having pivotal connections with the collar and the weight.
9. A movable support, an operating-shaft suitably journaled thereon, a lever-arm carried by the operating-shaft, a bracket adjustably mounted on the movable support, an eyebolt adjustable through a perforation of the bracket, a link having pivotal connection with the eyebolt, a weight having pivotal connection with the link, a collar adjustable on the lever-arm, and a link having pivotal connections with the collar and with the weight.
10. A movable support, an operating-shaft suitably journaled thereon, a lever-arm carried by the operating-shaft, a bracket mounted on the movable support, an eyebolt adjustable through a perforation of the bracket, a link having pivotal connection with the eyebolt, a weight having pivotal connection with the link, a collar on the lever-arm, a link having pivotal connections with the collar and the weight, and a weight on the lever-arm.
11. A movable support, an operating-shaft suitably journaled thereon, a lever-arm carried by the operating-shaft, a bracket mounted on the movable support, a weight suspended between the bracket and the lever-arm and connected therewith, and a second weight adjustable on the lever-arm.
12. A movable support, an operating-shaft thereon, a lever-arm carried by the operating-shaft, a bracket having a slotted extension adjustably secured to the movable support, and a weight suspended between the bracket and the lever-arm and connected therewith.

In testimony whereof we affix our signatures in presence of two witnesses.
